RECIPE FILE

Rose Hellman, Baxter Springs, Kans.

Application November 24, 1950, Serial No. 197,227

1 Claim. (Cl. 129—16)

1

This invention relates to a recipe file and like device for systematically filing of recipes, cards, names and other data according to a prearranged plan.

Housewives commonly cut recipes from magazines, newspapers and the like and then place the clipping loose in recipe books or boxes, however, such disposition of the clippings makes it difficult to locate same when needed and frequently results in loss of the recipes.

The objects of the present invention are to provide an inexpensive filing device having a plurality of pockets for systematically filing such recipes; to provide a file device with a plurality of pocket members removably and pivotally mounted on a support in overlapping relation for compactness and ease of reference and accessibility; to provide a file structure which is particularly adapted for economical and practical manufacture of the unitary elements and rapid assemblage of same; to provide a simple, resilient mounting of recipe holders or pocket members in spaced relation on a support for ease of removal and/or replacement thereof; and to provide a file structure adapted to be mounted on the wall of a room and support the pocket members in a vertical column for storage of a large number of recipes, cards and the like in a small space.

In accomplishing these and other objects of the present invention, I have provided improved details of structure, the preferred forms of which are illustrated in the accompanying drawings wherein:

Fig. 1 is a perspective view of a file structure embodying the features of the present invention.

Fig. 2 is an enlarged detail perspective view of the upper end of the file structure with portions broken away to illustrate the pocket mounting member.

Fig. 3 is a vertical sectional view through the file device.

Fig. 4 is a disassembled perspective view of a pocket member and mounting rod therefor.

Referring more in detail to the drawings:

I designates a recipe file embodying the features of my invention and consisting of a support or rack 2 having a plurality of pocket members or card holders 3 pivotally and removably mounted on the support in spaced overlapping relation. The support may be laid on a horizontal surface, however, it is particularly designed to be mounted on the wall of a room whereby the pocket members are in a vertical column or series. The

2

support 2 is preferably formed of sheet metal and has a rear wall 4 provided with a suitable aperture, such as a keyhole slot 5, adjacent one end 6 thereof for engagement with a suitable hook or nail in a wall for mounting the support thereon, the end 6 preferably being the upper end of the file structure.

The support includes spaced, parallel side walls 7 and 8 which are preferably integral with and extend forwardly from the side edges of the wall 4 to form a tray-like structure having an open front. The side walls 7 and 8 extend from the lower end 9 of the support and terminate as at 10 in spaced relation to the upper end 6. The upper corners of the rear wall 4 are preferably rounded as at 11 and the forward corners at the upper and lower ends of the side walls 7 and 8 are also rounded as at 12 to provide a neat appearance.

20 A plurality of clips or tongues 13 extend forwardly and upwardly from the front face 14 of the rear wall 4 for supporting the pocket members 3 as later described. The tongues are preferably arranged in a plurality of vertically spaced pairs, the tongues of each pair being laterally spaced and in alignment transversely of the wall 4, as illustrated in Fig. 2, whereby each pair of tongues is adapted to support a pocket member 3. The tongues 13 may be formed separately

25 and suitably secured to the wall 4 but are preferably each formed by making an inverted U-shaped cut in the wall 4 and pressing the tongue forwardly of said wall. Each of the tongues is curved upwardly and rearwardly to cooperate with the rear wall to form a seat 15 adapted to closely engage a pocket member supporting bar or rod 16. The upper ends 17 of the tongues are spaced from the front face 14 of the wall 4 slightly less than the thickness of the rod 16 and the tongues have some resiliency whereby

30 the rods may be pushed through the space between the tongue ends 17 and the wall 4 into the seats 15, and the resiliency of the tongues retains the rod in place. The rods 16 are preferably slightly shorter than the spacing between the side walls 7 and 8 whereby when the rods are located in the seats 15 the side walls limit longitudinal movement of the rods and prevent removal except through the space between the ends 35 of the tongues and the wall 4.

The pocket members 3 preferably are formed of sheet material, such as paper or the like, suitably folded and glued or stitched to form the pocket for containing recipes or the like. The pocket members may be constructed in the man-

ner of an ordinary envelope or as illustrated wherein the sheet of material is folded as at 18 to provide a front wall 19 overlying a rear wall 20. The adjacent side edges of the front and rear walls are secured together by adhesive and/or stitching and the upper edge of the front flap is unsecured to provide an opening 21 through which cards, clippings or the like may be inserted into the pocket formed between the front and rear walls.

The rear wall is provided with an extension or flap 22 which is folded rearwardly and secured as at 23 to the rear wall by suitable adhesive and/or stitching to form a loop 24 of suitable size to receive the bar 16 therein and permit the pocket member to be moved around the bar. Slots 25 are cut in the loop portion of the flap in the same spaced relation as the tongues 13, whereby said tongues enter the slots and do not interfere with pivotal movement of the pocket member when the pocket member carrying rod is located in the seats 15 formed by the tongues 13, as illustrated in Fig. 2.

In assembling the recipe file from elements constructed as described, the rods 16 are inserted and moved into the loops 24 of the pocket members 3. A rod with the pocket member thereon is then placed in engagement with the rear wall 4 of the support 2 adjacent a pair of tongues 13, with said tongues aligned with the slots 25. The rod is then pressed through the space between the ends 17 of the tongues and the wall 4, whereby the tongues move through the slots 25 and the rod engages in the seats 15. The pocket members 3 are narrower than the spacing between the side walls 7 and 8 whereby said pocket members may be moved therebetween and pivoted about the rod 16.

Additional pocket members are assembled on the support 2 in the same manner to provide a vertical series of overlapping pocket members as shown in Fig. 1. When it is desired to have access to one of the lower pocket members, the other pocket members thereabove are raised and pivoted around the respective rod 16 to expose the open upper end 21 of the respective pocket member and recipes or the like inserted therein or removed therefrom as desired. Also the entire pocket member may be removed from the support by pushing upwardly on the respective rod 16 to move same between the ends 17 of the tongues and the wall 4 to disengage the rod from said tongues. Also if the pocket members become worn they may be replaced in the same manner.

It will be obvious from the foregoing that I have provided an improved file for recipes, cards and the like, giving easy access to the contents

of the pocket members and also facilitating systematic filing of recipes and the like, said structure being economical to manufacture and easily maintained for efficient use.

What I claim and desire to secure by Letters Patent is:

In a device of the character described, an open front support having a rear wall and spaced forwardly extending side walls thereon, a plurality of pocket members formed of sheet material with the respective ends folded and secured to form a pocket having an open upper end and an open sided loop portion parallel and adjacent said open upper end of the pocket, said pocket members being of less width than the spacing of the side walls for free movement of said members therebetween and having a plurality of laterally spaced slots extending into the loop portion from the folded edge forming said loop portion, a rod removably and loosely mounted in the respective loop portions of each pocket member and extending through the open sides thereof substantially to the side walls whereby said side walls limit endwise movement of said rods, and a plurality of horizontally aligned resilient tongues integral with the rear wall and arranged in vertical series thereon between the side walls, said tongues being curved forwardly, upwardly and rearwardly and terminating in forwardly spaced relation to the rear wall with said spacing less than the thickness of the rod whereby the curved portion of the tongues form seats between the tongues and rear wall for resiliently receiving the rods, said horizontally aligned tongues being of a size and spacing to correspond with the respective slots in the pocket members and extend therethrough in releasable engagement with the respective rods for mounting the pocket members on the support in overlapped relation whereby the pocket members have limited endwise movement and pivot on the rods for access to the next lower pocket member.

ROSE HEILMAN.
